US0D1066429S

(12) **United States Design Patent** (10) **Patent No.:** **US D1,066,429 S**
(45) **Date of Patent:** **** Mar. 11, 2025**

(54) **BEAD SPINNER**

(71) Applicant: **Shenzhen Youqian Technology Co., Ltd.**, Guangdong (CN)

(72) Inventor: **Yuhua Zhuang**, Guangdong (CN)

(73) Assignee: **Shenzhen Youqian Technology Co., Ltd.**, Shenzhen (CN)

(**) Term: **15 Years**

(21) Appl. No.: **29/856,459**

(22) Filed: **Oct. 13, 2022**

(51) **LOC (15) Cl.** **19-06**

(52) **U.S. Cl.**

USPC **D19/111; D15/66**

(58) **Field of Classification Search**

USPC D15/66-78, 122, 138, 145

See application file for complete search history.

(57) **CLAIM**

The ornamental design for a bead spinner as shown and described.

DESCRIPTION

FIG. 1 is a perspective view of a bead spinner showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the bead spinner that form no part of the claimed design.

1 Claim, 8 Drawing Sheets
